UNITED STATES PATENT OFFICE.

JAMES C. MOCK, OF DETROIT, MICHIGAN.

RAILWAY-RAIL JOINT.

1,121,935.

Specification of Letters Patent.

Patented Dec. 22, 1914.

Application filed March 4, 1912. Serial No. 681,349.

To all whom it may concern:

Be it known that I, JAMES C. MOCK, a citizen of the United States, residing at Detroit, in the county of Wayne, State of Michigan, have invented certain new and useful Improvements in Railway-Rail Joints; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 This invention relates to railway rail joints especially designed for use in effecting insulated rail joints between the blocks of railway block signal systems, but adapted for other purposes, and consists in the 20 construction and arrangement of parts hereinafter more fully set forth and pointed out particularly in the claims.

The object of the invention is to provide simple and efficient means for enlarging the 25 surface at and adjacent the ends of the rails to afford greater splicing contact and provide for more rigidly joining the rail ends, provision being also made for effectively insulating the ends of the rail sections and 30 for protecting the insulating material against wear where the joint is employed as an insulating joint in railway block signal systems.

The above object is attained by the construction illustrated in the accompanying drawings, in which:—

Figure 1 is a fragmentary view in perspective of a railway joint constructed in accordance with my invention, showing how 40 said joint may be insulated. Fig. 2 is an elevation of Fig. 1. Fig. 3 is a transverse section as on line 3—3 of Fig. 2. Fig. 4 is a segregated view in perspective showing the members employed to enlarge the rail ends 45 and the splicing plate for spanning the joint at the meeting ends of the rail sections. Fig. 5 is a sectional view of a modified construction illustrating one method of enlarging the rail ends by casting thereon metal 50 to increase the surface area shaped to enable the application of the splicing bars to connect the ends of the rails.

Referring to the drawings by the characters of reference thereon, 1 designates the 55 railway rails of suitable cross-section. To

provide for enlarging the clamping surface of the rails at and adjacent the ends thereof said surface is increased by using the enlarging bars or members 2, which are bolted or riveted as shown at 3 by transverse bolts 60 passing through said bars and the web of the rail. These surface enlarging bars or members are of proper form in cross-section to cause the engagement of the upper edge thereof under the head of the rail and the 65 laterally extending base portion 4 thereof to bear upon the base of the rail. Each of the bars 2 is provided at the end adjacent the rail joint with a laterally extending flange 5 projecting from its upper edge, and with 70 an integral truss member 6 extending inwardly and downwardly from the outer edge of the base portion 4 so as to project under the base of the rail, said depending portion being provided in its outer face with 75 a longitudinally extending channel 7. The web of the enlarging bars is provided with apertures 8 for the securing bolts or rivets, and the depending truss portion thereof is provided with bolt or rivet apertures 9. 80 The joint is completed by employing the splicing plates 10 which are provided with an upper portion 11 adapted to cross the joint between the enlarging bars or members 2, and to lie between and have contact 85 with the upper flanges 5 and the base portion 4 of said bars, said splice plates having in said upper portion thereof the apertures 12 to receive the transverse bolts 13 which pass therethrough and through the enlarging bars and the rail. The central portion of 90 the splice plates curves outwardly as shown at 14 to pass around the base portion of the enlarging bars, the lower portion 15 of said splice plates being in alinement with the 95 upper portion thereof, and adapted to lie in the channels 7 of the truss portion 6 of said enlarging bars. Formed through the lower portion 15 of each splice plate are apertures 16 to receive the bolts 17 which pass there- 100 through and through the apertures 9 in the truss portion of the enlarging bars, whereby the parts may be securely clamped together, in which position they afford a firm support for the rail joint, the lower portion of the 105 splice plates lying in the channels 7 of the depending portion 6 of the enlarging members, serving to firmly truss said joint, as will be well understood. Where this construction is used as an insulating joint in 110

2
railway block signal systems, insulation 18 is introduced between the ends of the rails. Insulating material 19 is also introduced between the splice plates and surface of the 5 enlarging bars upon which they bear, and between the lower portion of said plates and the channelled truss members 6, while the bolts 13 and 17 are provided with bushing 20 and 21 respectively of insulating material. In this construction the clamping surfaces 10 are of such extended area that there is little or no rubbing friction between the parts, whereby the interposed insulation is relieved from wear, thereby greatly extending 15 the life thereof and obviating the liability of a defective joint, electrically, through destruction of the insulating material.

In Fig. 5 I have illustrated a mode of enlarging the rail ends by casting the enlarging members 2^a thereon instead of bolting or riveting them to the rail end as shown in the other views. In this arrangement the enlarging members might be formed integral 25 below the base of the rail as shown at 22. The splice plates 14 would be used in connection with the construction shown in Fig. 5, as illustrated in the other views, and insulation would be employed as in the other 30 constructions, where an insulated joint was to be made. While I have shown my invention applied to the ordinary T rail, it is obvious it may be applied to rails of other sections and while drawings in assembly 35 show insulating joints, I desire not to be confined to such, as it is also obvious the design is equally applicable to non-insulating rail joints.

Having thus fully set forth my invention, 40 what I claim as new and desire to secure by Letters Patent, is:—

1. In a rail joint, a pair of rails having adjacent ends, double channel or U shaped 45 bolting and bearing surface enlarging members embracing and securely fastened to the rail ends, splicing members to fit and cooperate with said enlarging members on four surfaces each of which makes an acute angle with the vertical plane through the 50 longitudinal axis of the rails, a plurality of fastening members for securing the splicing members and the enlarging members together, one of the four surfaces and some of the fastening members being located below 55 the bases of the rails, the whole arrangement serving to rigidly join the contiguous ends of the rails.

2. In a rail joint, a pair of rails having adjacent ends, double channel shaped enlarging members having portions depending 60 below the bases of the rails and embracing and securely fastened to the rail ends; splicing members to fit and coöperate with said enlarging members on four surfaces, each of 65 which makes an approximately equal angle

with a vertical plane through the longitudinal axis of the rails, two of the four surfaces being located below the base of the rails, means for rigidly securing the enlarging members and the splicing members to the 70 rail ends, and means for rigidly securing the splicing members to the enlarging members at a point below the bases of the rails.

3. In a rail joint, a pair of rails having adjacent ends, inner splicing members of 75 double channel cross-section fastened to the rails and coöperating with the bearing surfaces thereof and having portions depending below the bases of the rails, outer splicing members fitting against the outer surfaces 80 of the inner splicing members along four surfaces, each of which makes an approximately equal angle with the vertical plane through the longitudinal axis of the rails, means for independently fastening together the inner and outer splice members on each side of the rail, and means for fastening all 85 of the splice members to the adjacent ends of the rails to form a rigid joint.

4. In a rail joint, a pair of rails having 90 adjacent ends, a pair of bolting and bearing enlarging members of double channel cross-section embracing said rail ends, a splicing member engaging with the enlarging members along four surfaces each of which makes 95 an approximately equal angle with a vertical plane through the axis of the rails, two of the surfaces being located below the bases of the rails, means for fastening the enlarging members and the splicing member to the 100 rails, separate means for fastening the enlarging members and the splicing member together below the bases of the rails, and insulating material interposed between the enlarging and splicing members and between 105 the fastening means and the splicing member and also between the ends of the rails, the whole arrangement being such that the rails are rigidly joined together mechanically and separated electrically.

5. In a rail joint, a pair of rails having adjacent ends, discontinuous inner splicing members of double channel cross-section on each side of the rails, said inner splicing members having portions depending below 115 the bases of the rails, outer splicing members fitting against the outer sides of the inner splicing members along four surfaces each of which makes an approximately equal angle with the vertical plane through the longitudinal axis of the rails, means for independently fastening together the inner and outer splice members on each side of the rail, means for fastening all of the splice members to the adjacent ends of the rails, 125 and insulating material interposed between the outer splicing member and one of the inner splicing members, between one of the splicing members and the first mentioned fastening means, between one of the splic- 130

ing members and the second mentioned fastening means, and between the ends of the rails.

6. In a rail joint, a pair of rails having adjacent ends, inner splicing members of double channel cross-section on each side of the rails, said inner splicing members having portions depending below the bases of the rails, outer splicing members fitting against the outer sides of the inner splicing members along four surfaces each of which makes an angle with the vertical plane through the longitudinal axis of the rails, means for independently fastening together the inner and outer splice members on each
- 5 side of the rail, means for fastening all of the splicing members to the ends of the rails, and insulating material interposed between the ends of the rails, between the inner and the outer splicing members, between the 20 first mentioned fastening members and one of the splicing members and between the second mentioned fastening means and one of the splicing members.
- 10 In testimony whereof, I sign this specification in the presence of two witnesses.
